Primary Examiner — Robin V Webster(74) *Attorney, Agent, or Firm* — Ballard Spahr LLP(57) **CLAIM**

We claim the ornamental design for a sprinkler and coupling, as shown and described.

DESCRIPTION

FIG. 1 is a perspective view of a sprinkler and coupling showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the sprinkler and coupling that form no part of the claimed design.
